(57) **CLAIM**

The ornamental design for an electrical connector plug, as shown and described.

DESCRIPTION

FIG. 1 is a front, bottom, and left-side perspective view of an electrical connector plug according to a first embodiment of the present invention;

FIG. 2 is a front elevational view of the electrical connector plug shown in FIG. 1;

FIG. 3 is a rear elevational view of the electrical connector plug shown in FIG. 1;

FIG. 4 is a right-side elevational view of the electrical connector plug shown in FIG. 1;

FIG. 5 is a left-side elevational view of the electrical connector plug shown in FIG. 1;

FIG. 6 is a top plan view of the electrical connector plug shown in FIG. 1;

FIG. 7 is a bottom plan view of the electrical connector plug shown in FIG. 1;

FIG. 8 is a front, top, and left-side perspective view of an electrical connector plug according to a second embodiment of the present invention;

FIG. 9 is a front elevational view of the electrical connector plug shown in FIG. 8;

FIG. 10 is a rear elevational view of the electrical connector plug shown in FIG. 8;

FIG. 11 is a right-side elevational view of the electrical connector plug shown in FIG. 8;

FIG. 12 is a left-side elevational view of the electrical connector plug shown in FIG. 8;

FIG. 13 is a top plan view of the electrical connector plug shown in FIG. 8; and,

(Continued)

FIG. 14 is a bottom plan view of the electrical connector plug shown in FIG. 8.

In the drawings, the broken lines show portions of an electrical connector plug that form no part of the claim. The surface shading, if any, illustrated in the drawings is provided merely to highlight the contour of the design; it is not intended to be illustrative of texture or gloss.
